(57) **CLAIM**

The ornamental design for a packaging box, as shown and described.

DESCRIPTION

1. Packaging box

1.1 is a front perspective view of a packaging box in an unfolded state and in a closed position;

1.2 is a front view thereof, the back view being a mirror image;

1.3 is a left view thereof, the right view being a mirror image;

1.4 is a top view thereof;

1.5 is a bottom view thereof;

1.6 is a front perspective view of the packaging box in the unfolded state and in an open position;

1.7 is a front view thereof;

1.8 is a back view thereof;

1.9 is a left view thereof;

1.10 is a right view thereof;

1.11 is a top view thereof;

1.12 is a bottom view thereof;

1.13 is a front perspective view of the packaging box in a folded state;

1.14 is a front view thereof, the back view being a mirror image;

1.15 is a left view thereof, the right view being a mirror image;

1.16 is a top view thereof, the bottom view being a mirror image; and

1.17 is a front view of the packaging box in an intermediate state between the unfolded state and the folded state.

1 Claim, 17 Drawing Sheets
